HEATING APPARATUS WITH PROVISION
FOR UTILIZING COMBUSTION GASES

Ramón Castro Jiménez, Winthrop, Mass.

Original application July 17, 1940, Serial No.
345,966. Divided and this application May 29,
1943, Serial No. 488,962

8 Claims. (Cl. 158—28)

1

My present invention relates to the general class of heating and heat-exchange apparatus wherein the combustion of fluid fuel is accompanied by the giving off of exhaust gases of combustion, as for example in oil burner heating systems. More particularly the invention aims to improve the combustion efficiency and to reduce the fuel consumption for a given result. This application is a division of my copending application Serial No. 345,966, filed July 17, 1940, now Patent No. 2,320,821 dated June 1, 1943.

In the drawings illustrating examples of means embodying the invention as in an oil burner heating system,

Fig. 1 is a side elevational view of an oil burning furnace or boiler installation exemplifying novel means of the invention, as suitable for domestic and other building heating purposes;

Fig. 1a is a sectional view of a portion of the stack, on a larger scale, illustrating certain novel adjustable gas-trapping or collecting means of the present invention;

Fig. 2 is a top plan of the apparatus of Fig. 1; Fig. 3 is an enlarged vertical sectional view substantially on the line 3—3 of Fig. 4, looking toward the left in said figure, showing a typical rotary oil burner unit and certain associated means according to the invention, including particularly that for delivering a specially conditioned combustion gas mixture, also secondary air, to the burner;

Fig. 4 is a further view of the apparatus of Figs. 1 and 2, partly in plan and partly in horizontal section at a level just above the conditioning chest and with the upper portion of the boiler removed to expose the fire-pot and associated burner parts at the combustion locality;

Fig. 5 is a front end elevation of the conditioning chest, on the scale of Figs. 1, 2 and 4; and

Fig. 6, corresponding to Fig. 3, illustrates means of my invention including secondary air supplying means in association with an oil burner of the so-called gun type.

Referring to the drawings in more detail, and first to Figs. 1 and 2, I have there represented a typical modern boiler or furnace 10 having the usual provision for escape of the exhaust gases and products of combustion, including a breeching 11 and communicating stack 12 leading to a flue 13. While the invention is equally adaptable to heating or air-conditioning apparatus of any of the various types, including those wherein the circulating or heat-exchange medium may be steam, vapor, water or air, I have here chosen to illustrate it in connection with a hot-water radi-

2

ation heating system such as commonly used for heating dwellings and other buildings.

The water or other fluid circulating medium for the radiation system is heated in the boiler or furnace 10 through which it is circulated in the usual coils, cores, boiler sections and internal piping connections, not necessary here to show. The heated fluid medium, such as water, passes from the boiler through outlet piping 16 at the upper part thereof, see Figs. 1 and 2, communicating with one or more riser pipes such as 17 leading to the radiation system. The heat-supplying water is returned for reheating as through the return conduit 18, Fig. 4, communicating through branching return inlet pipes 19, 19a with the above-mentioned heating coils and associated water compartments in the boiler 10. An impeller or circulation-maintaining device may be provided, as indicated at 18a, Fig. 4.

20 The heating source for the boiler is represented as an oil burner unit indicated as a whole by the reference letter B, seen separately in Fig. 3. The invention is readily adaptable for use with any of the known types of oil burners, including 25 the so-called gun type. For the purposes of illustration I have here shown a so-called rotary burner installation, Figs. 1 to 5 and a gun type in Fig. 6. To avoid unnecessary detailed illustration and description of what may be standard equipment, it may be assumed that the boiler and the associated oil burner unit are of a standard commercial construction, for example, as represented by the Timken equipment known in the trade as model C.

30 As seen in Figs. 3 and 4, a combustion chamber is provided at the lower portion of the furnace or boiler assembly, said chamber including a flooring 20 of firebrick, clay or other suitable refractory or heat-resistant material. This flooring is disposed at a level above the cellar floor or other foundation adequate to provide a pit 21. The base of the burner unit, including supports 22 and framing 23, is disposed in the pit, the burner power unit or motor 24 being hung on the burner frame or platform 23, with its rotor axis disposed vertically. The motor shaft 25 is extended upwardly above the combustion chamber floor 20.

35 The rotary elements of the burner unit are concentrically disposed at the upper end of said motor shaft 25, the latter rotating in the counterclockwise direction as viewed in Fig. 4. Said elements include an annular cup 26 to which the incoming fluid fuel or oil is supplied from the fuel line 30a, a top plate 27, a series of radially 40 disposed discharge members 28 for the atomized

or vaporized fuel, and a circumferential series of vanes or fan elements 29. These latter in accordance with the invention are specially shaped and arranged for a purpose to be described. The combustion chamber floor 28 is provided with one or more through apertures of customary size, one of which is seen at 28a in Figs. 3 and 4, for admitting atmospheric air to the combustion chamber.

In addition I desirably provide in accordance with the invention a supplemental or secondary air inlet 31 comprising an upright tubular member or short section of pipe of suitable heat-resistant metal or other material. This supplemental air inlet is mounted in a through aperture in the combustion chamber floor 28 and is extended above the latter to or adjacent the combustion level so as to discharge in calculated relation to the rotary burner mechanism and to the discharge outlet 70 for the returning gaseous admixture to be more fully described. In this manner an adequate supply of oxygen to support combustion is assured in the region of the fuel delivery and combustion.

The oil feed line, leading from any suitable fuel oil supply (not shown) is indicated at 30. This fuel supply conduit 30, generally a copper tubing of about $\frac{1}{4}$ " diameter, has formed in or in communication with it, at a point adjacent the burner B, a coil 33. The end of this coil remote from the oil supply (with reference to the direction of flow) is continued as or connected to the pre-heated-oil delivery line 30a already mentioned in connection with Fig. 3. The coil 33 is disposed in a closed chamber or jacket 35 shown as of cylindrical form, see Fig. 5, having end walls or heads 36 or 37, through which the inlet and outlet connections for the coil with the fuel lines 30 and 30a, respectively, are extended in sealed condition.

The space within such chamber or jacket 35, externally of and surrounding the oil heating coil 33, is herein adapted to receive and circulate through it a portion of the heat-exchange medium of the radiation system associated with the boiler or furnace 10, such medium, as already noted, being of any of the various types, hot water being assumed in the example selected merely for the purposes of illustration. Accordingly, as best seen in Figs. 1 and 2, I provide a conduit for conducting such hot water or other medium from the boiler to the compartment 35 of the conditioning device, chest or retort, the latter as a whole being indicated by the reference character C. Such conduit may extend from any convenient point in a hot water circulation jacket or other compartment of the boiler or indeed may be comprised in a circuit separate from that of the radiation system, subject to heating in any convenient manner, as by the oil burner unit B of the furnace 10 or otherwise. As here shown an off-take conduit or pipe 38 is provided in communication with the outlet piping 16 for the heated water from the boiler, adjacent the riser pipe 17 of Figs. 1 and 2. It will be understood that the conditioning unit C may be disposed at any convenient location adjacent the furnace or boiler 10 and it is contemplated that in many instances, particularly in cases of initial equipment, as when a furnace is first installed in a newly constructed dwelling, that this conditioning unit C will be enclosed in or form a part of the furnace or boiler installation, so as to be enclosed in any exterior decorative or insulating casing for the heating or air-

conditioning apparatus as a whole. In other instances, such as where my system and apparatus are to be employed in conjunction with a previously installed burner and heating mechanism, the conditioning unit C will be disposed at the most conveniently available location adjacent the boiler, as upon the cellar flooring, substantially as represented in Figs. 1 and 2. In the illustrated example the hot water conduit 38 accordingly has an extension 39 in this instance directed downwardly and disposed to communicate with an inlet 40 on a wall of the inner compartment 35, herein the rear end wall 37.

Desirably a temperature-responsive control means is provided in association with the hot water conduit at some point between the heat source and the conditioning unit C. Where, as in the illustrated example, the domestic or other hot water supply is afforded from the same apparatus which supplies the heating medium for the radiation system, such temperature-responsive means may also serve as the control for the heating of such hot water supply. Accordingly, as best seen in Figs. 1 and 2, the hot water conduit 39 is operatively associated with a water supply heater-unit 41. This may be of the known type such as commonly installed for example with the Timken equipment previously referred to. Cool water from the main is supplied to this unit as though the supply pipe 42, the heated water being carried by a piping connection such as 43 to the various points of use in the dwelling or other building. Such unit has incorporated within it a thermostatic switch 44, for example as known by the trade name "aqua-therm," disposed in the electric circuit of the burner unit B and adjusted to switch off the burner whenever the water passing from the boiler through the pipe 39 reaches a predetermined maximum temperature, say in the vicinity of 150° F. In any event the thermostatic control setting is such, under my invention, that the oil in the pre-heater coil 33 generally does not acquire a temperature above 160° F. or whatever is the vaporization point of the particular fuel.

Leading from a portion of the oil-heating hot water compartment or chamber 35 remote from the inlet 40, herein at the front or end wall 36, is a return water conduit or pipe 45, whereby the water after passing about the coil 33 is re-conveyed to the boiler 10, as by connection with one of the return pipes 19 of the radiation system previously mentioned; see particularly Fig. 4.

The invention further contemplates conditioning, including pre-heating, of the air or the admixture of air and other gaseous matter which is supplied to the atomized or volatilized pre-heated fluid fuel and commingled with the latter to support and increase the efficiency of combustion at the burner.

Accordingly, as best seen in Figs. 1 and 1a, I provide means for trapping and taking off a quantity of the gases of combustion from the burner and which otherwise would pass off through the breeching 11 and stack 12 to the flue 13. Such means herein comprises a collecting device or gas trap 50 disposed in the stack 12 at a position calculated to afford adequate draft maintenance. In the illustrated example, said trap 50 is spaced somewhat above the breeching 11 and directly in the path of the gaseous combustion product travelling from the latter in the stack 12. The gas trap 50 is located in calculated relation to a thermostatic switch 12a disposed in the stack 12 and connected to shut off

the burner at a predetermined stack temperature. As here illustrated, see particularly Fig. 1, the gas trap 50 is set in the stack beyond said thermostat 12t, that is, between the latter and the flue 13. I have found in actual practice that reliable control and otherwise efficient operation are had when the trap is arranged with its mouth approximately four to six inches vertically above this thermostatic control device 12t.

Desirably, as shown, said gas-trapping device 50 is of adjustable capacity, so that the quantity or proportion of gases to be caught and diverted to the conditioning unit C may be variably controlled and set to suit the conditions at any given installation. As represented this device 50 comprises a main element or receiver 51 open at its lower and larger end 52 and decreasing in size toward its upper end 53, in the manner of an inverted cone or funnel. Its reduced upper end 53 is in closed communication with a laterally extending outlet or pipe 54 projecting through the wall of the stack 12 and herein affording support thereon for the trap device.

The receiver or collecting element proper 51 of this gas trap 50 is so constructed and disposed that sufficient draft to the flue is readily afforded. Its downwardly open mouth 52 is spaced from contact with the surrounding wall of the stack, to extents calculated and adjusted to the draft conditions of the particular installation, as for example an all-round spacing of approximately one inch; that is, in a ten-inch stack, the trap is adjusted to a maximum intake area of about eight inches in diameter. Further, said receiver or cone 51 is made perforate, over a substantial area of its lower portion, as by the series of perforations 55 of a size and total area calculated to preserve adequate draftage while accumulating and diverting the desired proportion of the combustion gases. In practice I have found that a multiplicity of perforations of approximately one-sixteenth to three-sixteenths of an inch in diameter and distributed around the skirt or main portion of the receiver 51 well serves the purpose. A spacing of about one inch between adjacent apertures is found suitable for most installations, as affording an appropriate ratio of draft-maintaining aperturing in combination with the peripheral spacing between the trap and the stack wall.

For variably adjusting the capacity of the trap 50 I have by way of example shown the skirt element 51 as split longitudinally upward from its mouth, as at 56, and said element is formed of a flexible metal or other heat-resistant sheet material such that the edges of the conical skirt along such split may be brought together into more or less overlapped relation or may be moved laterally out of such overlapping relation or even be spread and opened apart to adjustable extents, thereby in effect correspondingly changing the area of the trap mouth to the desired extent. Such adjustment may be performed by means such as an adjusting screw or rod 57 journaled on the stack 12 and having one or more threaded portions 58 operatively engaging a like number of lugs 59 on the split skirt 51. Turning of said adjusting rod, as by means of the manual adjusting knob 57a accordingly serves to move the split portions of the skirt toward or from each other and to hold them in adjusted position, to provide the appropriate area for the mouth of the trap, in spaced relation to the stack wall and in relation to the total area of perforation of the trap for draft main-

tenance as stated, the factor of draft output of the particular burner also being taken into consideration in the adjustment of the gas and heat trapping means described.

The gas trap off-take or outlet 54 is connected at its outer end to a downwardly extending pipe or gas conduit 60 through piping connections 61, 61 etc. of a non-abrupt-angular character, usually avoiding reverse bends, and of such direction and arrangement as to afford a free path of flow for the off-coming combustion gases subject to burner fan or blower means. At its lower end the conductor 60 is extended inwardly through a wall, herein one end wall of the outer compartment 62 of the conditioning unit C. Within the latter the gas supply conductor 60 terminates in an admission port 63, set inwardly from the compartment wall and spaced above in a vertical plane with the associated and herein inner chamber 35. Thus the gaseous combustion products, including any condensate that may be formed in the gas conduit 60 are conveyed and admitted to the main gas and herein outer chamber or compartment 62 of the conditioning unit C. Such moisture of condensation developing at the discharge outlet 63 of the gas conduit falls to and accumulates at the lower portion of the main chamber 62 where it may build up to the level of or somewhat above the bottom of the inner chamber 35, under usual atmospheric conditions, and in part is vaporized or revaporized as below further explained. Desirably a gauge of the liquid level, as indicated at 62a in Figs. 1 and 2, is provided, in communication with the lower portion of the main compartment 62, as is also a temperature gauge or thermometer 62b for readily determining the temperature conditions within said main compartment or outer chest 62.

In the operation of the system, vaporization of moisture in the main chamber 62 normally takes place, both from the previously collected or then accumulating body of moisture above mentioned and also from the depositing condensation moisture from the incoming gases, at the admission port 63. Such incoming moisture falls onto the then heated wall of the inner compartment 35, some portion thereof being vaporized or revaporized, to commingle with the original air content and with the gaseous combustion products circulating about the main compartment 62, while the remaining portion thereof collects into the body or accumulation of moisture at the lower portion of the main chamber 62 as already above indicated. Thus the gaseous product conducted from the trap 50 to the conditioning unit C is there mixed with initial air in the tank and with moisture or water vapor, with some degree of cooling by transfer to the usually relatively cooler water-circulating and oil-pre-heating chamber 35. In some instances such latter chamber may be otherwise located than as shown, but desirably in heat-subject relation to the recirculated combustion gases, or such chamber as 35 may be omitted, together with the water or other heating medium circuit, the fuel line then being directly rather than indirectly in heat-subject relation to the conserved combustion gases.

The described gaseous admixture thereafter is led from the main chamber of the conditioning unit C and is delivered to the combustion region of the oil burner unit B, at the discharge outlet 70 previously referred to in connection with Fig. 3, adjacent and subject to the action of the burner fan or air impeller. Said admixture, still heated, serves in effect to pre-heat the air for

7 supporting combustion and otherwise improved the efficiency of the combustive action...

Referring to Figs. 1 to 4, a conduit 71 for said humidified and otherwise conditioned gaseous admixture leads out from the main compartment 5 62 at a point remote from the admission port 63 for the combustion gases, herein in the opposite end wall of said main compartment. Such piping or conduit 71 includes appropriate connections or unions 72, 72, preferably of a non-abrupt angular character as referred to in connection with the gas conduit 60. The conduit 71 is continued through an opening 73 at the base of the furnace and admitting below the combustion chamber floor 20 to the pit 21 at any convenient 10 point, said conduit including a riser pipe 74 extending up through the combustion chamber flooring 20 and having at its upper end the directive outlet or discharge element 70 previously mentioned and located and directed in efficient subject relation to the burner primary air intake. As best seen in Figs. 3 and 4, said element 15 comprises an elbow which may be angularly adjusted upon the riser 74 so as to direct the heated gaseous discharge at the most efficient angle relative to the vanes 29 of the rotary air impeller 27-29 of the burner unit...

As above stated, said gaseous mixture outlet 70 is located in such proximity to the air impeller, whether of the rotary type of burner of Fig. 3 or the gun type of Fig. 6, as to be subject to the impelling or draft action. Desirably also, as here shown in Figs. 3 and 4, the air-moving blades or vanes 29 are of such area, generally somewhat larger than customary for the particular burner without my installation, and the blade construction and arrangement, particularly as to angular position with relation to the outlet 70, are made such as to insure a substantial or augmented impelling or draft action at said discharge outlet 70. 40 Such effect is made adequate, in consideration of and in proportion to the entire apparatus of my system, to create a draft action back through the gas conduit 70, the conditioning unit C and the downloading gas conduit 60 continuously to the 45 gas trap 50 within the stack, whereby during operation of the burner a continuous flow of the trapped gases of combustion is maintained from the stack to the combustion region.

Preferably I provide means for controlling the 50 force of this draft action. Herein, as best seen in Fig. 1, I have installed in the gas conduit 71 a manually adjustable valve 75, closing of which to a greater or lesser extent serves to vary and set the force of draft as appropriate to the particular installation and conditions. Or if at any time the 55 exhaust-gas-utilizing and air-pre-heating portion of my apparatus should be desired to be temporarily not employed, this may be accomplished by shutting off said valve 75 completely and desirably also another valve, not shown, adjacent the stack.

The gas supply line 71 may also conveniently be provided with an inspection and regulating port such for example as the cup or trap 76 connected in the conduit 71 and having a removable closure or cap 77; see particularly Fig. 1. By loosening or removing the cap 77 the character and force of the gaseous flow through the conduit 71 may be examined, for test and regulatory purposes. Said receptacle 76 may also serve to retain possible condensate produced within the relatively short length of conduit 71 between the boiler and the conditioning unit C, as may occasionally take place under conditions of extreme atmospheric 75

humidity. Any excess accumulation of such condensate may be relieved as by means of a bleeder aperture 78 at a low point in the conduit 71, also as best seen in Fig. 1.

Such bleeder aperture serves also for the admission and admixture with the gaseous flow to the burner of an additional amount of atmospheric air as may be found desirable for increasing the oxygen content. For the same purpose, one or more other air inlets may also be provided in the conduit 71, either adjacent the bleeder aperture 78 or elsewhere, for example as indicated at 79 in Figs. 1, 2 and 4. Such air inlet apertures generally have a diameter of about $\frac{1}{4}$ inch, depending somewhat upon the draft conditions at the particular installation, the size being reduced to approximately $\frac{1}{16}$ inch under exceptionally drafty basement conditions.

In a similar connection it is also here noted that the secondary or supplemental air inlet ducts adjacent the combustion point, such for example as represented at 20a and particularly at 31 in Fig. 3 are of calculated size, generally about $\frac{3}{4}$ inch diameter, again dependent in some measure on the given circumstances. It will be seen that in either the rotary type of Fig. 3 or the gun type of Fig. 6 that one or more such secondary air supply ducts within the fire box are provided, preferably at lower and upper levels respectively, one supplying air adjacent the lower portion of the flame and the other to the upper portion of the flame and combustion region. For example, the upper air inlet 31 of Figs. 1 to 5 has a length above the floor 20 of the combustion chamber of approximately five inches, thereby extending it to and delivering the air at the desired level in connection with a burner of the character there illustrated. Aside from the provision of such auxiliary or secondary air supply, little or no modification of existing types of burners is required, other than a modification of the fan or air impeller or enlargement and rearrangement of its blades in combination with the gas discharge conduit to afford the described circulation and recirculation of gases. A possible further exception, in view of the higher temperatures developed with my apparatus, may be a somewhat heavier and more heat resistant insulation for the burner electrodes. As in any instance, it is recommended that the burner nozzle be inspected periodically.

As above stated, the supplying of the recirculated combustion gases and pre-heated air may temporarily be shut off when desired, as by means of the valve 75. At such time, that is, when gases are not being taken from the stack, that portion of the pre-heating of the fluid fuel effected directly by the hot water or other heating fluid may be continued, or it also may temporarily be made nonoperative, merely by closing the shut-off valve 38a provided at any convenient point in the hot-water conduit 38; see Figs. 1 and 2. A similar valve may be disposed in the extension 39 of said hot water conduit, below the domestic water supply heater unit 41, in association with a valve controlled by-pass (not shown) communicating between said conduit 39 and the water return piping 49. Thus when desired the water heating unit 41 may be operated without either or both the fuel and the air pre-conditioning means of the invention.

It will be understood that the degree of pre-heating of the oil or fluid fuel is regulated for maximum efficiency of combustion. The proper oil temperature in the delivery line 39 generally

is found to lie in the range of about 120° to 145° F., depending somewhat on the particular circumstances of any given installation. The construction and arrangement of the preconditioning system as a whole and the incorporated control means are such that in no case will the temperature of the oil exceed about 150° F., leaving a safety factor of at least 10° below the critical temperature of approximately 160° F. As noted, the oil temperature may be variably controlled by means of the automatic temperature-responsive switch devices, including the thermoswitch 44 responsive to the temperature of the water en route to the unit C and the stack thermoswitch 12t subject to the temperature conditions adjacent the gas trap 50. Said stack thermoswitch 12t operates in the known manner, preferably in series with the relay coil of the motor switch device 30c, to stop the burner quickly in the event of a predetermined drop in stack temperature such as due to flame failure, also to cut off the burner in the event of undue continued rise in stack temperature above a selected degree. This device 12t desirably is of the type such as marketed under the name "Protectorelay" which is adapted to recycle in the event of flame failure, automatically giving the burner one chance to restart if other conditions are proper, but which does not permit the burner to deliver oil into a hot fire box until after a determined scavenger period for any accumulated gases and which period may be adjusted to suit the particular installation. If desired, means may be provided for readily visually determining the temperature in the outer compartment 62 of the conditioning unit C, such as the thermometer 62b, Figs. 1 and 2, mounted on said unit and subject to the heat condition in said compartment. It will also be understood that any and all of the controls or safety devices usual in an oil burner installation may be employed, including for example an automatic magnetic or other switch, relay or like device such as indicated at 30c at the lower left portion of Fig. 1 whereby the burner is completely shut off in the event of failure of the fuel supply.

From the foregoing it will be apparent that the method and system involved, as fully disclosed and claimed broadly in my copending parent application, utilize in combination the pre-heating of the oil or other fluid fuel and a pre-heating of the air supplied to the region of combustion together with an admixture with that air of a calculated portion of the combustion gases, conditioned by conduction, condensation, circulation in a confined space, some cooling by useful heat transfer and by subjection to moisture in liquid and vapor form, some of which may be admixed with the gases, which also receive a proportion of atmospheric air. Such trapped combustion gases are thus conditioned, circulated and recirculated to and from the burner. The outer compartment of the conditioning unit C and the received gases serve at the same time to maintain the desired heated condition adjacent the fuel coil. In cases where the pre-heating of the fuel in such coil 33 is directly effected by the hot water or other heating medium circulating from the boiler, there is also a mutual balancing and heat transferring or retransferring cooperation between the contents of the outer and inner compartments, including at times a booster effect upon the hot water or other fluid medium returning to the boiler.

In apparatus of my invention, there is attained under normal operation a materially closer ap-

proach to complete combustion of the fuel than in any commercial burner of which I am aware. Incidentally, it may here be noted that when initially starting from a completely cool status the burner system as here disclosed normally reaches its operating stage of maximum efficiency within a period of not more than about three minutes.

The remarkably improved combustion results are due to the combined effect of pre-heating not only the fuel but also the air for combustion while also mixing with it gases from the stack, conditioned as disclosed. And since a considerable part of the gaseous combustion product is returned for circulation and recirculation through the system, any unburned residue is constantly reduced. The total result is that even after an entire heating season little or no trace of soot is discernible in the boiler or stack. The flame at the burner is of the desired bluish-orange or sun-like character to which the term "turnasoline" is sometimes applied.

In Fig. 6 I have sufficiently illustrated an installation of my apparatus in connection with an oil burner B' of the so-called gun type. The apparatus in general may be the same as in the preceding figures, and parts not otherwise mentioned may be as previously described. In Fig. 6 corresponding parts have similar reference numerals as in Figs. 1 to 5 with the addition of a prime mark.

The burner B' is installed at the base of the furnace or boiler 10' in the usual manner, with the delivery or combustion end of the "gun" or burner casing extending inwardly through an appropriate aperture in the front wall. The particular burner illustrated, merely by way of example, is of the type such as shown in U. S. Patents Nos. D. 98,726, 2,066,651, 2,084,709 and others of that general class. Such burner is equipped with a rotary air impeller, the shaft of which is indicated at 25'. The supply line for the pre-heated liquid fuel or oil is seen at 30a', the oil flow being had in the usual manner, generally under the action of an oil pump operated by the burner motor and not seen in Fig. 6, being behind the impeller casing. The reclaimed and conditioned combustion gases coming from the chest or conditioning unit C such as that of Figs. 1 to 5, with the admixed pre-heated air, are conducted through the conduit 71' and delivered directly adjacent and within the influence of the impeller, the return outlet or delivery end of the conduit being indicated at 70'. As in the preceding figures such outlet 70' is angularly disposed for maximum efficiency of pick up of the gases, insuring their delivery to the combustion point in admixture with the air ordinarily supplied by the impeller.

Within the fire box and above a flooring 20' desirably provided for the combustion chamber, I provide one or more special or secondary air admission ducts, for generally similar purposes as the elements 20a and 31 of Figs. 1 to 5. Such air supply inlets are indicated in Fig. 6 at 80 and 81 respectively. Each has its outer end open to atmosphere at any convenient point outside the boiler or furnace 10', being here shown as extending inwardly through the front wall. One of said air supply ducts has its inner or air delivery end 80a disposed adjacent and below the flame or combustion point, said duct extending first through the heated space 21' below the combustion chamber floor 20'. The delivery end 81a of the other duct 81 also is adjacent the combustion region but herein above the flame of the burner. Thus

an adequate supply of oxygen to support combustion is assured.

The gas trap such as here shown is adapted for use otherwise than with the general class of burner installations, in conjunction with the conduct or utilization of combustion gases, as for example in my said parent application, now Patent No. 2,320,821.

It will be understood that my invention is not limited to the exemplary embodiments herein illustrated or described, and I set forth its scope in my following claims.

I claim:

1. In combustion apparatus having means forming a combustion chamber and communicating means providing a path for heated gaseous combustion products from the combustion region, a gas and heat interceptor device adapted for positioning in the path of such combustion products, said interceptor device comprising a cup-like body having an open mouth for entrance of such combustion products and an enclosing wall provided with a relatively smaller outlet aperture spaced from said mouth, a conduit in closed communication with said outlet aperture, the interceptor wall having therein a multiplicity of perforations for through passage of a portion of the gaseous products intercepted, and said interceptor body including means for adjustably varying the area of its mouth relative to the cross-sectional area of the path of gaseous combustion products in which it is to be positioned.

2. In combustion apparatus, in combination, means forming a combustion chamber having a communicating stack for gaseous products of combustion, a gas and heat baffle and collecting device disposed in the stack across the path of said combustion products, said device comprising a skirt element having a relatively large open end providing a mouth and a reduced opposite outlet for intercepted combustion products, the open end of the skirt element being laterally expansible and contractible variably to adjust the area of the mouth, the skirt element being disposed in spaced relation to the surrounding stack wall and having a multiplicity of relatively small perforations of a total area to preserve draftage in the stack while accumulating and diverting a portion of the combustion products, and means for variably adjusting the mouth area thereby to regulate the draftage.

3. For combustion apparatus having means forming a combustion chamber and a communicating stack, a heat and gas baffle and interceptor device adapted for installation in such stack, said device comprising an inverted cup-like element having a relatively large open mouth and having lateral and end wall means defining such mouth and providing a heat and gas receiving enclosure to which the mouth affords entrance, said wall means having therein a multiplicity of perforations for draft maintenance purposes, conduit means having closed communication with said cup-like element at a point spaced from its open mouth and adapted for supporting said element within and in spaced relation to such stack, and means for adjustably regulating the area of the open mouth of said element.

4. In fluid fuel combustion apparatus, means forming a chamber defining a region of combustion for a fluid fuel burner, rotary vane means for directing air admixed with fuel to the combustion region, a stack for the gaseous products of combustion extending from said chamber, interceptor means in the stack adapted to trap and

divert a selected portion of the gaseous combustion products while permitting draftage to be maintained, and a conduit leading from the interceptor means to and opening at a location directly subject to the influence of such rotary vane means in a manner to promote return flow and delivery of the diverted gaseous products to the combustion region.

5. In fluid fuel combustion apparatus, means forming a chamber defining a region of combustion for a fluid fuel burner, rotary vane means for directing air admixed with fuel to the combustion region, a stack for the gaseous products of combustion extending from said chamber, interceptor means in the stack adapted to trap and divert a selected portion of the gaseous combustion products while permitting draftage to be maintained, a conduit leading from the interceptor means to and opening at a location directly subject to the influence of such rotary vane means in a manner to promote return flow and delivery of the diverted gaseous products to the combustion region and means for adjusting the interceptor means to insure a selected draft action past the interceptor means.

6. In fluid fuel combustion apparatus, means forming a chamber defining a region of combustion for a fluid fuel burner, rotary vane means for directing air admixed with fuel to the combustion region, a stack for the gaseous products of combustion extending from said chamber, interceptor means in the stack adapted to trap and divert a selected portion of the gaseous combustion products while permitting draftage to be maintained, a conduit leading from the interceptor means to and opening at a location directly subject to the influence of such rotary vane means in a manner to promote return flow and delivery of the diverted gaseous products to the combustion region, and secondary air duct means leading from atmosphere to the combustion region and there having a delivery opening also subject to the influence of such rotary vane means.

7. In fluid fuel combustion apparatus, means forming a chamber defining a region of combustion for a fluid fuel burner, rotary vane means for directing air admixed with fuel to the combustion region, a stack for the gaseous products of combustion extending from said chamber, interceptor means in the stack adapted to trap and divert a selected portion of the gaseous combustion products while permitting draftage to be maintained, a conduit leading from the interceptor means to and opening at a location directly subject to the influence of such rotary vane means in a manner to promote return flow and delivery of the diverted gaseous products to the combustion region, secondary air duct means leading from atmosphere to the combustion region and there having a delivery opening also subject to the influence of such rotary vane means, and means for variably adjusting the interceptor means to regulate the proportion of the total gaseous combustion products to be trapped and diverted.

8. A gas and heat interceptor and deflecting device for installation in the stack of a combustion apparatus, said device comprising an inverted hood-like body of non-combustible wall-forming material open at the lower end to provide an inlet of relatively large area, the wall of said body above the inlet having a multiplicity of relatively small perforations affording through flow for a portion of stack gases entering at said inlet, said body having an outlet of an area relatively smaller

13

than and spaced oppositely to its inlet, an off-take conduit in closed communication with said outlet, and means for adjusting the open area of the inlet.

RAMÓN CASTRO JIMÉNEZ.
